CHURCH BELL TOLLER

Arthur C. J. Roy, New York, N. Y.; Mary Viault, New York County, N. Y., administratrix of said Arthur C. J. Roy, deceased, assignor to John H. Sadler, Coytesville, N. J.

Application December 17, 1946, Serial No. 716,823

6 Claims. (Cl. 177—288)

1

This invention relates to bell ringing devices for ringing or tolling church bells, chime bells, carillon bells, hour-striking bells and the like.

An object of the invention is to improve bell ringing devices.

Another object is to improve the devices for tolling or ringing church bells, chime bells, carillon bells, hour-striking bells and the like to render them simpler, more effective, more reliable, more durable and more automatic in operation.

A further object is to improve electric bell ringing and tolling devices.

A still further object is to provide a substantially balanced bell striker mechanism whereby the load on the actuating mechanism is reduced.

An additional object is to provide an adaptable bell ringer mechanism, the essential parts of which may be the same or substantially the same for ringers intended for mounting inside a bell and those intended for outside mounting.

Another object is to provide a bell striking mechanism which can readily and simply be adjusted to regulate the volume of sound emitted by the bell.

Other objects of the invention will be apparent from the following description and accompanying drawings taken in connection with the appended claims.

A feature of the invention resides in a striker mounting wherein the striker is pivoted on an arm and a substantial proportion of its weight is balanced by a counterweight or counterweights.

The arm is preferably mounted to come to rest in substantially vertical position. According to a further aspect of the invention an electric actuating mechanism is provided for accelerating the striker toward the bell and according to a still further feature the actuating mechanism is effectively decoupled from the striker to allow free swing thereof during the completion of the tolling stroke.

In the drawings:

Figure 1 is an elevation, partly in section, of a bell and electrically operated tolling mechanism therefor, and a diagram of the operating circuit therefor;

Figure 2 is an elevation, partly in section, of the tolling mechanism as viewed from the right in Figure 1;

Figure 3 is a sectional elevation on the line 3—3 of Figure 2;

Figure 4 is a side elevation of a modified bell and toller in which the bell is mounted for swinging and the toller is mounted outside the bell;

Figure 5 is an elevation of a bell, shown in

2

section, and a hand operated tolling mechanism.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Referring to the drawings, the bell 10 (Figure 1) which may be of cast bronze of conventional shape, is mounted and supported by a bolt 11 on a frame 12, which may be formed of wood timbers or structural steel members in a belfry of a church. The bell is suspended with its mouth downwardly directed.

The tolling mechanism, generally designated by the numeral 14, is mounted on a supporting iron bracket 13 which may be attached to a vertical support forming part of the frame 12. In some cases, where it is convenient to do so, the mechanism may be mounted directly on a horizontal frame member if it is suitably situated.

The tolling mechanism shown in greater detail in Figures 2 and 3, comprises a striker hammer 16 on the lower end of an arm 17 which is pivoted on a horizontal bolt 18 supported by a pair of iron brackets 19 bolted at 20 to the iron base plate 15, which is bolted to the supporting bracket 13. The arm 19 extends upward beyond the pivot and carries, at its upper end, a counterweight 21 formed of a stack of circular iron nuts 22 secured to the arm by a bolt 23 having its head countersunk in the arm. The nuts are threaded to screw onto the bolt and a lock washer 24 is interposed between the outermost nut and the rest of the stack to prevent unscrewing.

The hammer 16 and arm 17 are preferably integrally formed from a single iron casting to insure a permanent mounting for the hammer and the absence of any free-play under the repeated pounding encountered in use. The pivot hub 25 which is integrally cast with the arm 17 is bored with a transverse hole 26 (Figure 2) and the two ends are counterbored to provide seats of larger diameter in which are press fitted a pair of bronze bearing cylinders 27 which bear against the pivot bolt 18. Bolt 18 is preferably formed of stainless steel. This bearing provides a relatively low friction pivot for the hammer arm without the necessity of lubrication. This provides a trouble-free bearing requiring no attention over long periods of use or non-use and free of any tend-

ency to freeze or stick under extreme weather conditions.

Vertical brackets 19 are formed of heavy angle iron and each is provided at its lower end with a horizontal flange 28 integrally bonded to the vertical flanges. Flange 28 of each bracket is bolted by bolts 20 to base plate 15. Vertical flanges 29 of the brackets are positioned in spaced parallel relation on the two sides of the hammer 16 with sufficient spacing to allow the hammer 16 to swing freely between them.

As will appear later the arm 17 will come to rest in a substantially vertical position. A leather bumper 30 is secured by rivets 31 to an angle iron 32 bolted to base plate 15. The bumper is mounted in a position to stop the hammer in substantially vertical position on its return swing after striking the bell.

An actuating lever 33 for the striker arm 17 projects rearwardly from the side of the arm above the pivot hub 25. The lever is secured to the arm by bolts 34. The lever is formed to provide a curved track 35 comprising a segment of a circle having its center at the axis of rotation of striker arm 17 and a block chain 36 is mounted to lie along this curved track. The body of lever 33 is formed to provide a recess 37 of generally triangular form merging with the upper end of the track 35 and the uppermost block or link of the chain 36 is folded back as shown so that the folded end fits within the triangular recess. It will be noted that this affords a secure anchorage for the upper end of the chain and that any downward pull on the chain will be resisted by the abutment of the folded-over link of the chain against the wall of the triangular recess 37.

The body of lever 33 is built up as shown at 38 along one-side of track 35 to provide a flange which will prevent lateral displacement of the chain from the track. A cover plate 39 is secured over the recess 37 and extends down alongside the track 35 to provide a second retaining flange for the chain.

The chain 36 supports the armature or plunger 41 of a solenoid 40 mounted on base plate 15 immediately below the lever arm 33. The chain is secured to the plunger by link connection comprising a screw 42 connected to the lowermost link of the chain and threaded into a block 43 which is bolted in a slot in the upper end of the plunger by a cross bolt 44. The chain thereby serves as a flexible link connecting the plunger of the solenoid to the lever. If it is desired to adjust the effective length of the chain and thereby change the setting of the plunger within the solenoid this can readily be accomplished by removing the cover 46 and then removing plunger 41 from solenoid 40 and screwing or unscrewing the block 44 on screw 42 for a few turns until the desired adjustment is obtained. As little as one half turn change can be effected.

The plunger 41 is formed of soft iron (which may be laminated, if desired) and consequently is pulled downward into the passage through the center of the solenoid whenever the solenoid is electrically energized. In accordance with one aspect of the present invention the plunger is provided with a mechanical stop to limit its travel into the solenoid. This is accomplished by making the plunger substantially T-shaped so as to provide a pair of arms 45 at the upper end of the plunger. When the solenoid is operated the plunger is drawn into the solenoid until arms 45 engage the upper end of the solenoid, which then stops the downward travel of the

plunger. It will be apparent that other forms of stop can be provided such a stop member of plate at the bottom of the recess in the solenoid.

A protection cover 46 of sheet metal is secured over the solenoid and plunger.

The solenoid 40 may be adapted for operation from house current, such as alternating or direct current of 110 or 220 volts or any other power supply available. Figure 1 shows, by way of example, one electric circuit arrangement for operating the solenoid. This comprises a relay 47, the contacts of which control the supply of current to the solenoid from an A. C. or D. C. power supply circuit 48. The relay 47 is itself controlled by a manual switch 49 which may be manually operated to complete relay energizing circuit 50 from a power source, such as a 110 volt power line. Manual switch 49 may in some instances comprise one of the keys of a manual keyboard, in which case the other keys of the keyboard will control the ringing or tolling of other bells. Thus a complete system for the ringing of a set of chime bells and the rendering of chime music is provided. It is also possible, by a simple contact making arrangement to provide for the ringing of the bell or bells by a clock.

The mass of the counterweight 21 is adjusted by varying the numbers and size of circular nuts 22 until its weight, added to the weight of the lever 33, plunger 41 and upper end of arm 17, slightly less than counterbalances the weight of hammer 16 added to the weight of the lower end of arm 17. Expressed differently, the torque applied about the pivot by the hammer 16 exceeds the torque applied by the counterweight plus the torque applied by the plunger when the solenoid is de-energized by an amount sufficient to bring the arm 17 into substantially vertical position against the friction of the bearing. The hammer 16 will thus tend to come to rest with arm 17 in a vertical position and with the back of the hammer against leather bumper 30.

As an example of one embodiment of the invention a hammer weight of 50 pounds having its central axis 8 inches from the pivot is provided with a 38 pound counterweight having its central axis 7 inches from the pivot. The plunger, chain and lever arm add to the counterweight a torque equal to about 5 pounds acting on a $2\frac{1}{2}$ inch radius. It will be apparent that as the hammer arm swings toward the vertical position with the solenoid de-energized the effective torques of the hammer weight and counterweight about the pivot will decrease due to the shortening of their distance from the vertical plane through the pivot. However, the torque of the de-energized plunger remains constant due to its constant radius of leverage. However, the hammer projects out from one side of the arm and the counterweight from the opposite side, so that the arm is brought to a substantially vertical position against the friction of the pivot. A suitable solenoid for a 50 pound hammer will have a maximum pull, when energized, of about 110 pounds, and one for a 12 pound hammer a pull of 35 pounds. Solenoids of standard sizes can be used and the impulse imparted to the hammer adjusted by varying the length of plunger travel before it strikes the stop.

In operation, whenever the solenoid is energized by operation of key 49 and relay 47 the plunger is pulled downward with a force sufficient to rotate arm 17 on its pivot thereby accelerating hammer 16 toward the bell. Due to the circular curvature of track 35 the leverage of the actuator

ing mechanism comprising plunger 41 and chain 36 is kept constant throughout the pull stroke of the plunger. At its preferred setting the plunger starts its pull at a position where approximately 85% of the maximum force or strength of the solenoid is realized. As the stroke continues the force applied by the solenoid to the plunger increases due to the closer coupling of plunger and solenoid bringing about a reduction in the air gap of the magnetic circuit.

When the hammer has traveled through part of its swing toward the bell but has not yet struck the bell the plunger is brought to a stop in its downward travel by arms 45 coming into contact with the top of the solenoid. This completes the plunger stroke but the hammer 16, having been accelerated by the pull of the plunger continues its travel toward the bell. As the swing of the hammer arm 17 continues the chain 36 will slacken and fall into a loop or bow thereby, in effect, decoupling the plunger from the hammer arm. The hammer continues to swing freely until it strikes the rim of the bell. The completion of the stroke toward the bell is unimpaired by the weight or friction of the plunger and hence the hammer is entirely free in its swing and is free to rebound without interference so that a single clear, clean bell tone is emitted. The quality of the tone is similar to that produced by a single full swing of a clapper in tolling a bell. This is also due in part to the fact that the tolling mechanism is mounted in a position which will cause the hammer to strike the bell rim with a stroke perpendicular to the surface of the bell.

On the rebound of the hammer 16 from the bell the slack of chain 36 will be taken up by the rotation of the arm until a lifting force is applied to the plunger 41. If the solenoid is still energized the magnetism will resist the lifting force and will bring the arm to a halt with hammer 16 in a position midway between the bell and the stop 39. However, the hammer will not again be swung to strike the bell until the operating key 49 is released and then pressed a second time.

When the solenoid is de-energized, either before or after the hammer arm return has taken up the slack in the chain the hammer will swing back to the leather bumper 38 and come to rest.

Adjustment of the length of the plunger stroke by screwing or unscrewing members 42 and 43 will adjust the strength of the impulse applied to the hammer during a single actuation of the bell tolling mechanism and hence vary the loudness of the sound emitted by the bell.

Figure 4 illustrates a modification of the invention to provide a tolling mechanism for a swinging bell. The bell 51 is mounted in a yoke 53 to swing about a horizontal axis 55 which is in the plane of the paper (as seen in Figure 4) and has a swinging clapper 52 mounted within the bell in the usual manner. The bell is provided with the usual actuating wheel for manual ringing with a pull rope or may be arranged for operation by an electric motor drive mechanism.

The tolling mechanism 54 is generally similar to mechanism 14, but in this case the tolling hammer 56 is at the upper end of the arm 57 and the counterweight 51 is at the lower end. The counterweight torque in this case applies a torque about the pivot axis 55 which exceeds the torque applied by the hammer and plunger, the proportions being similar to, but in the reverse of those previously described in connection with the mechanism of Figures 1, 2 and 3.

The mechanism 54 is, in this instance, mounted

outside the bell on a cross piece 57 of the timber framework supporting the bell, and is positioned to the side of the bell and immediately below the swinging axis 55 so as to be outside the path of swing of the bell when it is rung. The tolling mechanism 54 is allowed to remain inactive during ringing of the bell by swinging.

When it is desired to toll the bell the bell swinging mechanism is allowed to remain inactive so that the bell hangs in the vertical rest position illustrated. The tolling mechanism is then electrically actuated in the same manner as previously described to swing the hammer 56 against the rim of the bell, the hammer, in this instance striking the outside of the rim with a perpendicular blow to achieve the preferred tonal qualities in the tolling of the bell.

A bell ringing and tolling arrangement is thus provided as shown in Figure 4 in which the bell can be rung in the usual manner when it is desired to give a ringing tone and in which the bell can be tolled by the tolling mechanism at times when this is desired. Due to the fact that, in swinging, the mouth of the bell projects the sound directly out of the openings of the belfry or bell chamber a cheerful tone of varying intensity is produced. During tolling, however, the mouth of the bell is directed downwardly into the base of the chamber or tower and due to the resonance of the chamber a more pensive tone is produced. The different tones are used at different times depending on the customs of the church or other institution in which the bell is used. By mounting the tolling mechanism as shown in Figure 4 it is ready for use at any time and yet does not interfere or obstruct the normal ringing of the bell.

Figure 5 illustrates a further modification of the invention in which the tolling mechanism 64 is arranged for manual actuation by pull rope 71. The rope is fastened at its upper end to an eye 74 in the lower end of a pull-rod 73 which extends through an opening 70 in the bed-plate of mounting bracket 63. The upper end of pull-rod 73 is provided with a rubber or leather stop member 75 which may comprise a doughnut ring or a washer clamped to the pull-rod. This stop member 75 is larger than the opening 70 so as to limit the length of the downward stroke when the bell is tolled. The pull rod is suspended by chain 66 from actuating lever 33 as previously described. The length of chain 66 is so adjusted that stop member 75 will engage the base plate of bracket 63 before the hammer 16 strikes the bell so that the hammer will swing freely in completing its stroke.

The relative masses of hammer 16 and counterweight 21 are adjusted to bring the hammer arm 17 to rest in a substantially vertical position in the same manner as described in connection with the mechanism of Figures 1, 2 and 3. In this instance the weight of the pull-rod 73 and pull-rope 71 will correspond to the residual pull of plunger 41 in the de-energized condition resulting from its weight and any residual magnetism of the solenoid.

It will sometimes be desired, for reasons of economy or due to lack of an electric power supply to install the manual tolling mechanism of Figure 5 at one time and later to convert it to electric operation. This can readily be done by replacing the pull rope and pull rod of Figure 5 with the solenoid and plunger of Figure 1, and making any required adjustment in the mass of

the counterweight to provide the preferred torque relationship.

It will be evident from the foregoing that an efficient tolling mechanism has been provided requiring much less force and power for operation due to its substantially balanced mounting. It is thus possible to utilize a relatively small solenoid to toll a bell of several tons in weight and having a heavy striking hammer and, in the case of manually tolled bells the pull required of the bell man is greatly reduced. However, the actuating mechanism does not interfere with the free swing of the hammer on completion of the stroke and on rebound.

The mechanism is substantially foolproof in operating and of durable construction which will provide years of service without attention or lubrication.

The volume and tone can be readily regulated by an adjustment of the length of the pull stroke of the plunger or the manual pull-bar.

The present invention is applicable to manual or electric operation of church bells, tolling bells, Angelus bells, chime bells, carillon bells, hour striking bells of all sizes, ranging from bells of a few inches in diameter to those of several feet in diameter and many tons in weight.

While the present invention, as to its objects and advantages, has been described herein as carried out in specific embodiments thereof, it is not desired to be limited thereby but it is intended to cover the invention broadly within the spirit and scope of the appended claims.

What is claimed is:

1. A tolling bell comprising, in combination, a depending bell having a flaring opening at the bottom, a support including a horizontal pivot within said bell, an arm pivoted thereon by means of a bearing cooperating with said pivot, said bearing being located between the ends of said arm, a hammer weight at the lower end of said arm positioned to strike the inside of the rim of said bell upon rotation of said arm to a position in which the arcuate path of said hammer is substantially perpendicular to the surface of the flange of said bell, a counterweight on the upper end of said arm, a downward force applying element having an energized and a de-energized condition, a lever on said arm and an actuating link suspending said element from said lever to apply a torque to said arm to accelerate said hammer weight toward striking relation with said bell responsive to the energization of said force applying element, stop means to limit the downward travel of said force applying element whenever said hammer passes beyond a predetermined point in its travel toward said bell before striking said bell, said link means including means to effectively decouple said force applying element from said lever to permit said hammer to swing freely toward said bell after said force applying element reaches said stop, the centers of gravity of said hammer weight and said counterweight being substantially on a straight line passing through said pivot, the torque applied about said pivot by said counterweight exceeding the torque applied thereto by said hammer plus the residual torque applied by said force applying element in the de-energized condition by an amount sufficient to bring said arm to a substantially vertical position against the friction of said bearing on said pivot, and a bumper mounted on said support in the path of travel of said hammer to stop said arm in a substantially vertical position upon the rebound of said hammer from said bell.

2. A tolling bell comprising, in combination, a depending bell having a flaring opening at the bottom, a support including a horizontal pivot outside said bell, an arm pivoted thereon by means of a bearing cooperating with said pivot, said bearing being located between the ends of said arm, a hammer weight at the upper end of said arm positioned to strike the outside of the rim of said bell upon rotation of said arm to a position in which the arcuate path of said hammer is substantially perpendicular to the surface of the rim of said bell, a counterweight on the lower end of said arm, a downward force applying element having an energized and a de-energized condition, a lever on said arm and an actuating link suspending said element from said lever to apply a torque to said arm to accelerate said hammer weight toward striking relation with said bell responsive to the energization of said force applying element, stop means to limit the downward travel of said force applying element whenever said hammer passes beyond a predetermined point in its travel toward said bell before striking said bell, said link means including means to effectively decouple said force applying element from said lever to permit said hammer to swing freely toward said bell after said force applying element reaches said stop, the centers of gravity of said hammer weight and said counterweight being substantially on a straight line passing through said pivot, the torque applied about said pivot by said counterweight exceeding the torque applied thereto by said hammer plus the residual torque applied by said force applying element in the de-energized condition by an amount sufficient to bring said arm to a substantially vertical position against the friction of said bearing on said pivot, and a bumper mounted on said support in the path of travel of said hammer to stop said arm in a substantially vertical position upon the rebound of said hammer from said bell.

3. A bell toller comprising, in combination, a support including a horizontal pivot, an arm pivoted thereon by means of a bearing cooperating with said pivot, said bearing being located between the ends of said arm, a hammer weight on one end of said arm, a counterweight on the opposite end of said arm, force applying means having an energized and a de-energized condition, actuating link means connecting said force applying means to said arm to apply an actuating torque thereto about said pivot to accelerate said hammer weight responsive to energization of said force applying means, said force applying means applying a residual torque to said arm when said force applying means is in de-energized condition, the centers of gravity of said hammer weight and said counterweight being substantially on a line passing through said pivot, the torque applied about said pivot by one of said weights exceeding the torque applied thereto by the other of said weights plus the residual torque of said force applying means by an amount sufficient to bring said arm to a substantially vertical position against the friction of said bearing on said pivot, said link means including means to effectively decouple said force applying means from said arm whenever said arm passes beyond a predetermined point in its travel from vertical position, whereby said arm will be substantially free-swinging beyond said point.

4. A tolling bell comprising, in combination, a depending bell open at the bottom, a support including a horizontal pivot, an arm pivoted thereon by means of a bearing cooperating with

said pivot, said bearing being located between the ends of said arm, a hammer weight on one end of said arm positioned to strike the rim of said bell upon rotation of said arm through a small angle from the vertical position thereof, a counterweight on the opposite end of said arm, force applying means having an actuated and an unactuated condition, actuating link means connecting said force applying means to said arm to apply an actuating torque thereto about said pivot to accelerate said hammer weight toward striking relation with said bell responsive to the actuation of said force applying means, said force applying means applying a residual torque to said arm when said force applying means is in unactuated condition, the centers of gravity of said hammer weight and said counter-weight being substantially on a line passing through said pivot, the torque applied about said pivot by one of said weights exceeding the torque applied thereto by the other of said weights plus the residual torque of said force applying means by an amount sufficient to bring said arm to a substantially vertical position against the friction of said bearing on said pivot.

5. A tolling bell comprising, in combination, a depending bell open at the bottom, a support including a horizontal pivot, an arm pivoted thereon by means of a bearing cooperating with said pivot, said bearing being located between the ends of said arm, a hammer weight on one end of said arm positioned to strike the rim of said bell upon rotation of said arm through a small angle from the vertical position thereof, a counterweight on the opposite end of said arm, force applying means having an actuated and an unactuated condition, actuating link means connecting said force applying means to said arm to apply an actuating torque thereto about said pivot to accelerate said hammer weight toward striking relation with said bell responsive to the actuation of said force applying means, said force applying means applying a residual torque to said arm when said force applying means is in unactuated condition, the centers of gravity of said hammer weight and said counterweight being substantially on a line passing through said pivot, the torque applied about said pivot by one of said weights exceeding the torque applied thereto by the other of said weights plus the residual torque of said force applying means by an amount sufficient to bring said arm to a substantially vertical position against the friction of

said bearing on said pivot, and a bumper mounted on said support in the path of travel of one of said weights to stop said arm in a substantially vertical position upon the rebound of said hammer from said bell.

- 5 6. A tolling bell comprising, in combination, a depending bell open at the bottom, a support including a horizontal pivot, an arm pivoted thereon by means of a bearing cooperating with said pivot, said bearing being located between the ends of said arm, a hammer weight on one end of said arm positioned to strike the rim of said bell upon rotation of said arm through a small angle from the vertical position thereof, a counterweight on the opposite end of said arm, force applying means having an actuated and an unactuated condition, actuating link means connecting said force applying means to said arm to apply an actuating torque thereto about said pivot to accelerate said hammer weight toward striking relation with said bell responsive to the actuation of said force applying means, said force applying means applying a residual torque to said arm when said force applying means is in unactuated condition, the centers of gravity of said hammer weight and said counterweight being substantially on a line passing through said pivot, the torque applied about said pivot by one of said weights exceeding the torque applied thereto by the other of said weights plus the residual torque of said force applying means by an amount sufficient to bring said arm to a substantially vertical position against the friction of said bearing on said pivot, said link means including means to effectively decouple said force applying means from said arm whenever said hammer passes beyond a predetermined point in its travel toward said bell before striking said bell, whereby said arm will be substantially free-swinging at the instant of striking said bell.
